STOKER APPARATUS

Robert A. Foresman, Prospect Park, Pa., assignor to Westinghouse Electric & Manufacturing Company, East Pittsburgh, Pa., a corporation of Pennsylvania

Application August 26, 1942, Serial No. 456,217

15 Claims. (Cl. 122—4)

This invention relates to stokers, more particularly to those of the progressive feed type, and has for an object to provide improved apparatus of this character.

Another object of the invention is to provide, in a progressive-feed stoker, a fuel-supporting surface downwardly inclined in the direction of fuel feed and unbroken from top to bottom by steps, ledges, etc., to which clinker formations might adhere.

A further object of the invention is to provide a water-cooled multiple retort stoker whose tuyère rows present a smooth fuel-supporting surface.

Yet another object of the invention is to provide an improved tuyère construction embodying air distribution passages.

A further object of the invention is to provide a novel tuyère assembly embodying one or more conduits for flow of cooling medium.

These and other objects are effected by my invention as will be apparent from the following description and claims taken in connection with the accompanying drawings, forming a part of this application, in which:

Fig. 1 is a side elevational view, partially in section, with portions thereof broken away for the sake of clearness, and illustrating one embodiment of the present invention;

Fig. 2 is an enlarged fragmentary view of a stoker tuyère row embodying the invention;

Fig. 3 is a transverse sectional view taken along the line III—III of Fig. 2, looking in the direction of the arrows;

Fig. 4 is a similar view taken along the line IV—IV of Fig. 2, looking in the direction of the arrows;

Fig. 5 is a view similar to Fig. 4 showing the parts thereof in exploded position; and,

Figs. 6 and 7 are transverse sectional views taken along the lines VI—VI and VII—VII, respectively, of Fig. 2, looking in the direction of the arrows.

Referring to the drawings in detail, there is shown a furnace 10 having a front wall 11 through which fuel is fed from the hopper 12 by a ram (not shown) housed within the ram box 13 and operated by the conventional stoker engine 14. Fuel fed through the front wall is advanced from front to rear of the furnace by an underfeed stoker 16, comprising alternately-disposed retorts 17 and tuyère rows 18. The retorts and tuyère rows are followed, in the direction of fuel feed, by an overfeed section 19, comprising a plurality of pivotally-connected

bars 21 adapted to have undulatory motion imparted thereto by links 22 and crank arm 23, the latter being operated from the stoker engine mechanism. Air under pressure for combustion purposes is supplied to the plenum chamber 24, located beneath the underfeed section of the stoker, by the air supply conduit 26, in the customary manner.

Referring now to Figs. 2 to 5, inclusive, each tuyère row is comprised by spaced side walls 27 having inwardly-directed flanges 28 at their upper edges providing upper supporting surfaces 29, these surfaces preferably being inclined downwardly from the front toward the rear of the furnace. The space 31 between the side walls 27 is in direct communication with the plenum chamber 24 therebeneath.

A row of longitudinally-aligned lower tuyère members 32 are supported upon the upper edges 29 of the side walls 27 and bridge the space 31, each tuyère member having an opening 33 therethrough for passage of air from the space 31 and the plenum chamber 24. Also, each member 32 has, extending upwardly from its upper surface, a centrally-disposed boss 34, and, at each side of the latter, pegs 36 and lugs 37. A row of longitudinally-aligned upper tuyère members 38 rests upon and is supported by the row of lower tuyère members 32, and the members 38 are provided with downwardly-projecting bosses 39, pegs 41 and lugs 42, adapted to bear upon the corresponding bosses 34, pegs 36 and lugs 37 of the lower tuyère member 32.

It will be apparent that the assembled upper and lower tuyère members have therebetween tortuous lateral passages between and around the pegs and lugs, providing for flow of air from the plenum chamber 24 and through the opening 33 in the lower tuyère member to the side edges of the assembled tuyères.

The upper tuyère members 38 are provided with longitudinally-extending grooves or channels 43 in their upper surfaces, adapted to closely receive a pair of tubes 44 for passage of cooling medium. While these tubes are supported intermediate their ends by the upper tuyère members 38, their terminal portions are mounted in and carried by upper and lower end castings 46 and 47, respectively.

A row of longitudinally-aligned tuyère cap members 49 is disposed in overlying relation to the tubes 44 and the upper and lower tuyère members 38 and 32, the cap members having grooves or channels 49 in their under surface adapted to closely embrace the upper portions of

the tubes 44. Preferably, the tuyère cap members are provided with a convex upper fuel-supporting surface 51, and the side edges of the upper and lower tuyère members 38 and 32 are shaped to form approximate continuations of the outline of the tuyère cap member, whereby there is provided a tuyère assembly which presents a relatively smooth fuel-supporting surface throughout the length of the tuyère row, with the result that there is little or no tendency or opportunity for clinker formations to adhere thereto.

The various tuyère members are held in assembled relation by suitable means, such as the stud 52, threadedly secured in the tuyère cap member, at 53, and extending through vertical aligned openings 54 and 55 formed in the upper tuyère members 38 and the lower tuyère members 32, respectively. The studs likewise pass through an opening 56 in the center of a clamping bar 57, the nut 58, washer 59 and spacing sleeve 61 serving to clamp the three tuyère elements and the tubes 44 in unitary relation. The spacing bar 57 is of such length as to be closely received between the opposed flanges 28, thereby serving to prevent lateral displacement of the tuyère assembly with respect to the side walls 27.

The tuyère upper end casting 46 is formed in two halves 66 and 67 for the sake of ease of manufacture, the halves 66 and 67 being provided with chambers 68 and 69, respectively, adapted to communicate with the upper or discharge ends of the tubes 44. Horizontally-disposed air passages 71 are provided above the chambers 68 and 69, and have laterally-directed exhaust or tuyère passages 72, the passage 71 receiving air from the plenum chamber by way of the space 31 between the tuyère row side walls 27 (Fig. 2). The uppermost portions of the castings 66 and 67 are flattened, as at 13, to provide a horizontal supporting surface for the conventional air distribution box structure 74 and are provided at their bottom edges with supporting flanges 76 having depending lugs 77 at the inner edges thereof, the flanges 76 being adapted to rest upon the flanges 28 of the tuyère lower side walls, with the depending lugs 77 abutting the inner edges of the flanges 28, whereby lateral displacement of the castings is prevented.

The side walls of the castings are provided with a plurality of air discharge passages 78, 79 and 81 for flow of combustion air from the plenum chamber 24 and space 31.

In order to better interlock the castings 66 and 67 and to prevent fine fuel from passing downwardly through the joint therebetween, the casting 66 is provided with a laterally-projecting lip 82 adapted to be received in a mating rabbet 83 formed in the casting 67.

The lower hollow end casting 47 is of a construction very similar to that just described for the upper end casting except that the flattened upper surface 13 and the air passages 71 and 72 are lacking. The two halves 84 and 86 have chambers 87 and 88, respectively, communicating with the tubes 44 and with supply passages 89 which, together with the pipes 91, conduct cooling fluid from the horizontal header 92. Cooling medium thus supplied to the tubes 44 discharges from the latter through the upper end casting 46 and then, by way of pipes 93, 94 and 95, is conducted to the heat exchanger 96 where the heat taken from the tuyère assembly by the fluid passing through the tubes 44 is removed from such

fluid and the latter returned to the supply header 92 by the pipes 98, 99, 100, 101 and 102.

In order to complete the cooling of the tuyère construction for the entire stoker, the side wall tuyères 104 may have cooling tubes 105 arranged in heat transfer relation thereto, cooling medium being supplied through pipes 106 and 107 and led away by pipes 108 and 109 communicating with the heat exchanger 96.

While in the embodiment herein illustrated, the tuyère assembly has been shown as provided with cooling means, it will be apparent to those skilled in the art that there may be conditions or circumstances where the use of the cooling tubes 44 may be dispensed with, in which case the grooves or channels 43 and 49 in the upper tuyère member 38 and the tuyère cap member 48 may be omitted and the tuyère cap member 48 may be formed integral with the upper tuyère member 38, if desired.

While the invention has been shown in but one form, it will be obvious to those skilled in the art that it is not so limited, but is susceptible of various changes and modifications without departing from the spirit thereof, and it is desired, therefore, that only such limitations shall be placed thereupon as are specifically set forth in the appended claims.

What is claimed is:

1. A furnace stoker comprising alternately-disposed retorts and tuyère rows, each of said tuyère rows comprising a pair of spaced side walls and a tuyère assembly bridging the space therebetween; said tuyère assembly comprising a plurality of lower tuyère members having openings therethrough for passage of air from the space between the side walls; said members extending from one side wall to the other and being supported thereby; a plurality of upper tuyère members carried by the lower tuyère members; said upper and lower members providing therebetween passages for flow of air laterally from the openings through the lower tuyère members; and a plurality of tuyère cap members overlying said upper tuyère members and providing a smooth upper fuel-supporting surface for each tuyère assembly.

2. Structure as specified in claim 1, including means for liquid cooling said tuyère assembly.

3. Structure as specified in claim 1, including a tube for conducting cooling fluid disposed longitudinally of each tuyère row in heat transfer relation to the tuyère assembly and protected by the tuyère cap members from exposure to fuel burning in the furnace.

4. Structure as specified in claim 1, including a tube for conducting cooling fluid extending longitudinally of each tuyère row between the upper tuyère members and the tuyère cap members in heat transfer relation thereto.

5. Structure as specified in claim 1, including a pair of cooling fluid tubes extending longitudinally of each tuyère row in side-by-side relation, and means for clamping said tubes between the upper tuyère members and the tuyère cap members, whereby said tubes are protected by the tuyère cap members from burning.

6. In an underfeed stoker, a plurality of spaced retorts having side walls, the adjacent side walls of adjoining retorts being spaced apart to provide air spaces; a plurality of lower tuyère members supported by said adjacent side walls and bridging the air spaces therebetween; said members having openings therethrough for flow of air from said air spaces; a plurality of upper tuyère mem-

bers assembled on the lower tuyère members, said upper and lower members providing therebetween lateral passages communicating at their inner ends with said openings for receiving air from the air spaces and discharging at their outer ends at the lateral edges of the assembled tuyère members; and a plurality of tuyère cap members overlying the assembled upper and lower tuyère members and providing a smooth fuel-supporting surface.

7. Structure as specified in claim 6, including lugs extending into the lateral passages and rendering the latter tortuous.

8. Structure as specified in claim 6, including upwardly-projecting pegs on the lower tuyère members and downwardly-projecting pegs on the upper tuyère members, said pegs being adapted, when the tuyère members are assembled, to extend into the lateral passages and render the latter tortuous.

9. Structure as specified in claim 6, including means for liquid-cooling the tuyère members.

10. In an underfeed stoker, a plurality of spaced retorts having side walls, the adjacent side walls of adjoining retorts being spaced apart to provide air spaces; a plurality of lower tuyère members supported by said adjacent side walls and bridging the air spaces therebetween; said members having openings therethrough for upward flow of air from said air spaces; a plurality of upper tuyère members carried by the lower tuyère members; said upper and lower members providing therebetween lateral passages for flow of air from the openings through the lower tuyère members to the lateral edges of the assembled members; conduits for cooling medium supported on the upper tuyère members and extending longitudinally in substantially parallel relation to the upper edges of the retort side walls; and tuyère cap members overlying the conduits and providing fuel-supporting surfaces thereabove.

11. Structure as specified in claim 10, includ-

ing means for retaining the upper tuyère members and the tuyère cap members in heat transfer relation to the conduits.

12. Structure as specified in claim 10, wherein each row of tuyère members has a pair of parallel conduits associated therewith.

13. Structure as specified in claim 10, including means for retaining the tuyère lower and upper members, the tuyère cap members and the conduits in assembled relation as composite units.

14. Structure as specified in claim 10, including means for retaining the tuyère upper, lower and cap members and the conduits in assembled relation as composite units and for preventing lateral displacement of said units with respect to their supporting retort side walls.

15. A furnace stoker comprising alternately-disposed retorts and tuyère rows, each of said tuyère rows comprising a pair of spaced side walls whose upper edges are inclined downwardly from the front of the furnace towards the rear and a tuyère assembly bridging the space between said side walls; said tuyère assembly comprising a row of lower tuyère members having vertical openings for passage of air therethrough from the space between the side walls; said lower tuyère members resting on the inclined side wall upper edges in longitudinal alignment and bridging the space between said walls; a row of upper tuyère members supported by said lower tuyère members; said upper and lower tuyère members providing therebetween lateral passages for flow of air from the vertical openings of the lower tuyère members; and a row of longitudinally-aligned tuyère cap members overlying the upper tuyère members and having convex upper surfaces providing a downwardly-inclined fuel-supporting surface which is smooth from top to bottom, whereby free fuel-bed movement thereover may occur.

ROBERT A. FORESMAN.
